UNITED STATES PATENT OFFICE.

WILLIAM G. LEE AND ALBERT E. KING, OF CLEVELAND, OHIO, ASSIGNEES TO BROTHERHOOD OF RAILROAD TRAINMEN, A FRATERNAL BENEFICIAL ASSOCIATION OF OHIO.

DESIGN FOR AN EMBLEM.

40,384.

Specification for Design.

Patented Dec. 7, 1909.

Application filed September 15, 1909. Serial No. 517,957. Term of patent 14 years.

To all whom it may concern:

Be it known that we, WILLIAM G. LEE and ALBERT E. KING, citizens of the United States, residing at Cleveland, in the county of Cuyahoga and State of Ohio, have invented a new, original, and ornamental Design for Emblems, of which the following is a specification, reference being had to the accompanying drawings, forming part thereof.

The figure is a front view showing our new design for emblems.

We claim:

The ornamental design for an emblem, as shown.

WILLIAM G. LEE.
ALBERT E. KING.
